DENTAL APPARATUS

Oscar H. Pieper, Rochester, N. Y.

Application April 27, 1932, Serial No. 607,759

26 Claims. (Cl. 4—262)

The present invention relates to dental apparatus and has for one object to provide in conjunction with dental equipment stands, pedestals, and the like, improved means for protecting the same against the effects of drippings discharging from various liquid holding parts connected with or carried by the stands as a result of condensation due to the differences in temperatures at the exterior surfaces of the parts and the liquids or fluids therein, such as are provided for use by the dentist in connection with the treatment and care of the teeth.

A further object of the invention is to provide in conjunction with either fixed or movable parts of the apparatus through which the liquid or fluid is permitted to flow, one or more receptacles for the condensate dripping from the liquid holding parts in all positions thereof and also to provide means for carrying off the drippings discharging to the receptacles.

A further object of the invention is to provide an improved mounting for a waste basin or other receptacle including a hollow or tubular support forming a liquid discharge conduit for carrying off the liquid from the basin and having associated therewith a liquid supply connection arranged to swing with the support about the axis thereof.

A further object of the invention is to provide an improved arrangement of liquid supply and discharge connections for a cuspidor bowl and other liquid receiving devices, and also to provide means for intercepting and carrying off the condensate discharging from one or more of the connections.

A further object of the invention is to provide improvements in the construction and mounting of drip catching receptacles and the like for use in conjunction with dental equipment stands for receiving the condensate forming on certain liquid supply or discharge conduits or other liquid holding parts carried by or connected with the stand.

To these and other ends the invention resides in certain improvements and combinations of parts, all as will be hereinafter more fully described, the novel features being pointed out in the claims at the end of the specification.

In the drawings:

Fig. 1 is a side elevation of a dental equipment stand embodying one form of the invention;

Fig. 2 is a sectional elevation taken substantially on line 2a—2a of Fig. 1;

Fig. 3 is a horizontal section taken approximately on line 3a—3a of Fig. 1;

Fig. 4 is a fragmentary elevation drawn to an enlarged scale with certain parts shown in section; and

Fig. 5 is a fragmentary sectional elevation of a modified form of the invention.

The same reference numerals throughout the several views indicate the same parts.

The invention relates to dental apparatus and more particularly to improvements relating to dental equipment stands or pedestals of the type adapted to support a variety of dental equipment adjacent the dental chair, including in part the cuspidor bowl, the drinking glass stand and waste basin, and the liquid supply and discharge conduits associated therewith, any of which parts may be of the fixed or movable type. Serious objections have been encountered in this class of apparatus owing to disfiguration and injury of the base or pedestal by the continued dripping thereon of the condensate accumulating on certain overlying parts containing the fluid or liquid used in connection with the treatment of the teeth.

The stand or pedestal is usually provided with a coating of enamel and it is found that the condensate dripping from the different parts through which the liquid flows often causes the enamel to crack off at different points. This is particularly true with respect to any exposed edges of

the pedestal with which the drippings come in contact or at points where the enamel is relatively thin. A further objection to the dripping of the condensate upon the pedestal is that dust accumulates on the surfaces over which the liquid flows and as the liquid dries the dust hardens

leaving streaks or spots which are very noticeable and which disfigure and spoil the appearance of the unit. Another serious objection is that where the pedestal is made of aluminum, the condensate upon cracking of the enamel will attack the aluminum causing it to corrode, this being particularly true in parts of the country

where different alkalis and other foreign substances are present in the water. Means for overcoming the objections pointed out above, in a practical and satisfactory manner and without detracting from the appearance of the dental unit will subsequently be described.

The invention also contemplates improved mountings and connections for the water supply leading to and from the cuspidor and the drinking glass stand and other parts as set forth hereinafter.

Referring to the drawings, 10 represents a hollow supporting column or pedestal preferably

110

in the form of a casting which rests at its bottom on a base 11. The pedestal branches at its upper end into oppositely arranged arm-like extensions 12 and 13, the former of which is designed to support different dental equipment units, such, for example, as an electric motor and an instrument tray, not shown. The extension 13 forms a support for the cuspidor bowl 14 and also a hollow arm or support 15 having thereon a waste basin 16 and a drinking glass stand or holder 17. The arm 15 is preferably disposed directly over the upper wall or central body portion 18 of the pedestal lying between the opposing extensions 12 and 13 and shaped in cross-section as best shown in Fig. 2.

The water for flushing the cuspidor and for the drinking supply is carried upwardly through a supply pipe 19 disposed within the pedestal and extending through the wall 18 thereof as shown in Fig. 4 where it is connected with an overlying head 20. Extending from the head is a connection 21 which leads into the arm 15 and is connected therein with a suitable valve, a portion of which is indicated at 22, Fig. 4. Connected with and extending from the valve into the cuspidor bowl is a pipe 23 terminating in a nozzle 24 for discharging water to the bowl to flush the same. The drinking glass, not shown, which is carried by the stand or holder 17 is supplied with water by means of a pipe 25 connected with the valve and extending from the arm 15 upwardly above the waste basin 16 in position to discharge thereto. The waste basin is in communication with and discharges through the arm 15 beneath the cuspidor outlet, the latter being provided with a suitable trap, not shown, which depends from the flared portion 26 of an annulus 27 seated on the upper face of the hub 15a of the arm, Fig. 4. The lower reduced portion of the cuspidor 14 extends within the annulus and is preferably secured by cementing it therein, the annulus being prevented from turning by means of a pin 28 projecting within the wall of the hub 15a as shown in Fig. 4.

A drain pipe 29 is positioned within the pedestal for carrying off the water discharging from the cuspidor and the basin 16, the pipe having its upper end projecting within the extension 13 of the standard and connected therein with a fixture or mounting 30 for holding the arm 15 and bowl 14 upon the pedestal. The mounting has a flange 31 overlying the extension 13 and rests upon a gasket 32 thereon which affords a liquid tight joint between the parts. The mounting 35 also has a flange 33 slightly larger than the flange 31 which is disposed within and rests upon the annular shoulder 34a of a ring 34 into which is threaded the extension 35 on the hub 15a of the arm 15. The bottom of the ring is seated upon the horizontal portion 36 of the receptacle 37 for receiving the condensate which accumulates on the arm and which discharges therefrom into the receptacle, the latter being also seated upon the gasket 32 on the pedestal extension 13 as shown in Fig. 4. The mounting 30, in addition to forming the mouth of the drain pipe 29 also functions as means for securing the ring 34 and receptacle 37 upon the pedestal extension 13. For this purpose a screw or bolt 38 is threaded within a lug 39 on the mounting, the screw being extended through the horizontal wall portion 40 of the pedestal upon which the head of the screw rests. By tightening the screw it will exert a downward pull on the mounting, thus firmly clamping the flange 31 thereof upon the extremity of the ex-

tension 13 and also securing the flange 33 upon the shoulder of the ring 34 which in turn serves to secure the receptacle 37 upon the extension. With this construction the arm 15 carrying the waste basin 16 and the cuspidor bowl 14 is secured upon the pedestal, the arm discharging directly into the mounting, which forms a common outlet for the water flowing from the cuspidor bowl and the waste basin, and which together with the mounting and the conduit 29 forms a drain connection for the basin 16 and the bowl 14.

The means for preventing the condensate which accumulates upon and discharges from the arm 15 from descending upon the pedestal is in the form of a receptacle 41 arranged beneath the arm and overlying the curved body portion 18 of the pedestal as clearly shown in Figs. 1 and 2. The receptacle is of the elongated dish-shaped type, designed to conform generally in outline to the curve of the upper body portion 18 of the pedestal. The receptacle is so formed as not to detract from the appearance of the unit which has been constructed to afford an attractive and pleasing design which is highly desirable in equipment of this kind. The receptacle is supported in spaced relation to the wall 18 of the pedestal by a pair of lugs 42 the lower ends of which rest upon seats 42a on the wall 18, the lugs being connected with the wall by screws 43 extending downwardly through the lugs and threaded into said wall.

At the lowest point of the receptacle an outlet opening 44 is provided which leads into a drain pipe 45 extending through the wall 18 of the pedestal and connected with a boss 46 on the bottom of the receptacle. The lower end of the pipe 45 is attached to a connection 47 carried by the drain pipe 29 with which the connection communicates through passages, not shown, whereby the condensate discharging from the arm 15 and from the water supply connections leading thereto is carried off as fast as it accumulates.

The water supply pipe 19 is extended through the upper wall 18 of the pedestal and also through the bottom wall of the receptacle 41, as shown in Fig. 4. The bottom of the receptacle at the point through which the pipe extends is provided with a sleeve-like portion 48 projecting within an opening formed in the wall 18 of the pedestal as best shown in Fig. 4. Surrounding the pipe within the sleeve is a flanged bushing 49 preferably constructed of flexible or yieldable material and affording a liquid tight joint between the pipe and sleeve while at the same time sealing the opening in the bottom of the receptacle through which the pipe extends.

The end of the receptacle nearest the pedestal extension 13 is disposed beneath the edge of the receptacle 37 on the extension and the condensate accumulating in the last mentioned receptacle is discharged through an opening 50 in the wall thereof to the elongated receptacle 41 overlying the central body portion of the pedestal. It will be seen, therefore, that means is provided for receiving and carrying off all of the condensate which drips from the arm 15 and associated parts, and that the pedestal is thus protected against injury and disfigurement by the drippings.

The main difference in the modification shown in Fig. 5 over that shown in the remaining figures is that the arm 15 instead of being fixed against movement on the pedestal extension 13 is mounted for a swinging movement about the axis of the cuspidor bowl in order that the waste basin and drinking glass stand may be readily adjusted to

different positions for use by the patient. This makes it necessary for the drip-catching receptacle which extends beneath the arm to move with the latter and requires also that the horizontal section of the water supply pipe leading to the valve within the arm be mounted to swing with the arm about the axis thereof. In the modified construction the parts similar to those of the preferred construction are given corresponding reference characters. In this modified construction the mounting 30a receives the liquid discharging from the cuspidor 14 and arm 15 and the flange 31 of the mounting is clamped upon the gasket 32 by tightening the bolt 33. The flange 34a of the ring 34 extends beneath the flange 33 of the mounting and is free to rotate upon a ring-shaped bearing plate 51 resting upon the upper face of the drip-catching receptacle 37. The hub 15a of the arm 15 is provided with an extension 52 which has an exteriorly threaded reduced portion 53 screwed into the ring 34 and secured against turning therein by one or more set screws 54. With this construction the arm 15 and the parts thereon including the bowl 14, extension 52, 25 and the ring 54, are free to rotate about the axis of the mounting 30a and while the mounting is clamped upon the pedestal extension it does not prevent rotation of the parts superimposed thereon, it being understood that the receptacle 37 is 30 fixed to the pedestal extension by suitable means such for example as one or more screws 37a.

The mounting 30a, which is preferably in the form of a casting, has on its vertical wall oppositely arranged communicating tubular members 55 and 56, the latter terminating at its upper end on the axis of the arm 15 and having a coupling 57 rotatably receiving a short pipe 58 from which extends a horizontally disposed pipe 59 the outer end of which is connected with the head 20 on the pipe 21 leading to the valve 22 within the arm 15. The pipe 59 at the point where it passes through the extension 52 of the hub 15a is sealed by a bushing 60 affording a liquid tight joint between the parts. The water supply pipe 19 is connected with the tubular portion 55 of the mounting 30a by means of a coupling 61. With the construction just described it will be apparent that the arm 15, the cuspidor 14, the basin 16 and other parts connected with the arm including the water supply connections above the tube 56, are free to swing about the axis of the pedestal extension 13 to any position desired with respect to the dental chair most convenient to the patient or the operator.

The means for receiving the condensate accumulating upon the arm 15 and water supply connections therebeneath preferably comprises an elongated receptacle 62 underlying said parts and inclined to the horizontal so that it will readily drain into receptacle 37 over which the inner end of the receptacle 62 extends in any position of the arm 15 and associated parts. The receptacle 62 may be suspended beneath the arm 15 by any suitable means, but is preferably carried by the head 20 with which the water supply pipes 21 and 59 are connected, the receptacle being provided with boss-like portions 63 through which extend screws 64 threaded within the wall of the head 20 at the under side thereof.

The drippings discharging from the opening 50 of the receptacle 37 are received by the flared portion 65 of a short drain tube 66 extending downwardly through the wall 18 of the pedestal and received within a sleeve 67 suitably formed on the drain pipe 29 and in communication there-

with. The drain tube 66 is provided with a lug 68 resting upon the wall portion 18 of the pedestal and secured thereon by a screw 69.

In the modified construction shown in Fig. 5 it will be apparent that the condensate discharging from the arm 15 and associated parts will be intercepted by the receptacles 62 and 37 and will be carried off by the drain pipe 66 to the discharge pipe 29 thus preventing the possibility of the discharge of the condensate upon any portion of the pedestal, regardless of whether or not the arm 15 is in the position shown or overlies the upper central portion 18 of the pedestal, as it may do at different times under different operating conditions.

An important feature of the construction shown in the modified form of the invention aside from the provision of the drip-catching receptacles, is the novel manner of combining the water supply and drain pipes whereby the extension of the supply pipe 19 is carried through the mounting 30a on the drain pipe 29 and constructed to receive and permit rotation of the short connection 58 on the horizontal supply pipe 59 which is rigidly connected with the arm 15 and rotates with the latter to the different positions to which it is adjusted. Furthermore, the mounting 30a also functions as a means for securing the cuspidor 14 and arm 15 upon the pedestal extension 13 while at the same time permitting rotation of said parts upon the pedestal extension.

I claim:

1. In dental apparatus, an upstanding pedestal, a hollow support extending horizontally from and connected with the pedestal, a receptacle on the outer end of the support, means for supplying liquid to the receptacle from which it is discharged through the support, and means spaced from the receptacle and extending horizontally beneath the support and connected with the pedestal, said means being arranged to receive the condensate forming upon and discharging from the exterior surface of the support.

2. In dental apparatus, a pedestal comprising a body portion having an extension thereon, a hollow arm overlying said body portion and having one end connected with the extension, means arranged to deliver liquid to the other end of the arm, a receptacle beneath the arm overlying the body of the pedestal arranged to receive the condensate forming upon and discharging from the exterior surface of the arm, and means within the pedestal connected with the receptacle for conveying the liquid therefrom.

3. In dental apparatus, a hollow pedestal having a body portion provided with an opening in its wall, a hollow arm overlying the body portion and having an outlet in registry with said opening, a discharge conduit within the pedestal communicating with said outlet through the opening, means arranged to deliver liquid to the arm for discharge therethrough to said conduit, and a receptacle beneath the arm overlying the body of the pedestal and arranged to receive the condensate accumulating upon and discharging from the exterior surface of the arm.

4. In dental apparatus, a hollow pedestal having a body portion provided with an opening, drip catching means overlying the body of the pedestal and including a portion surrounding the axis of the opening, a hollow liquid receiving arm overlying the drip catching means and having its outlet end disposed adjacent the opening, and a discharge conduit communicating with the outlet

- end of the arm through the opening, said drip catching means being arranged to receive the condensate accumulating upon and dripping from the exterior surface of the arm.
5. In dental apparatus, a hollow pedestal having a body portion provided with an opening, a hollow arm overlying said body portion and having its outlet end in registry with the opening, a discharge conduit within the pedestal communicating with the outlet end of the arm through the opening, means on the arm for receiving a supply of liquid arranged to deliver the liquid to the arm for discharge therethrough, liquid supply means extending through said opening and discharging into the liquid receiving means on the arm, and means overlying the body of the pedestal and extending beneath the arm arranged to receive the condensate accumulating upon and discharging from the exterior surface of the arm. 80
10. 6. In dental apparatus, a hollow pedestal having a body portion provided with an opening, a hollow arm overlying said body portion and having its outlet end in registry with the opening, a discharge conduit within the pedestal communicating with the outlet end of the arm through the opening, means on the arm for receiving a supply of liquid arranged to deliver the liquid to the arm for discharge therethrough, liquid supply means extending through said opening and discharging into the liquid receiving means on the arm, and means overlying the body of the pedestal and extending beneath the arm arranged to receive the condensate accumulating upon and discharging from the exterior surface of the arm. 85
15. 7. In dental apparatus, a hollow pedestal having a body portion provided with an opening, a hollow arm overlying said body portion and having its outlet end in registry with the opening, a discharge conduit within the pedestal communicating with the outlet end of the arm through the opening, means on the arm for receiving a supply of liquid arranged to deliver the liquid to the arm for discharge therethrough, a receptacle interposed between the outlet end of the arm and the portion of the pedestal having the opening therein, the receptacle being arranged to receive the condensate accumulating upon and discharging from the exterior surface of the arm, and means for receiving and carrying off the liquid accumulating within the receptacle. 90
20. 8. In dental apparatus, a hollow pedestal having a body portion provided with an opening, a hollow arm overlying said body portion and having its outlet end in registry with the opening, an outlet conduit within the pedestal communicating with the outlet end of the arm through the opening, means on the arm for receiving a supply of liquid arranged to deliver the liquid to the arm for discharge therethrough, a receptacle interposed between the pedestal and the arm arranged to receive the condensate accumulating upon the arm and discharging therefrom, and means arranged to receive from the receptacle the condensate discharging thereto and to deliver the same to said outlet conduit. 95
25. 9. In dental apparatus, an upstanding pedestal, a hollow arm connected with and arranged to swing upon the pedestal, a receptacle on the arm in communication therewith, means for delivering liquid to the receptacle for discharge through the arm, and means mounted upon the arm to swing therewith, said means underlying the arm and arranged to receive the condensate forming upon and discharging from the exterior surface of the arm. 100
30. 10. In dental apparatus, a hollow pedestal having an extension provided with an opening, a liquid outlet conduit within the pedestal having its receiving end connected with the extension within the opening, a hollow arm connected at one end with said conduit end, a basin on the arm in communication therewith, means for delivering liquid to the basin, a receptacle on the extension surrounding the receiving end of the outlet conduit, and a second receptacle extending beneath the arm and arranged to receive the condensate accumulating upon and discharging from the arm and to deliver the same to the first mentioned receptacle. 105
35. 11. In dental apparatus, a hollow pedestal having an extension thereon, a drip-catching receptacle mounted upon said extension, a hollow arm having its outlet end connected with the extension and overlying the receptacle, a liquid discharge conduit projecting within the extension and communicating with the outlet end of the arm, and a second receptacle beneath the arm arranged to receive the condensate accumulating upon and discharging from a portion of the arm, said second receptacle being arranged to discharge the liquid received therein to the first mentioned receptacle. 110
40. 12. In dental apparatus, a hollow pedestal having an opening formed in its wall, a hollow arm connected with the pedestal and arranged to swing thereon about the axis of the opening, a discharge conduit communicating with the arm, means for delivering liquid to the arm for discharge therethrough, a receptacle surrounding the axis of the arm adjacent the point of connection of the arm with the pedestal, and a second receptacle secured beneath the arm arranged to swing therewith and to receive the condensate accumulating on and discharging from the exterior surface of the arm, said last mentioned receptacle being arranged to discharge the liquid received thereby to the first mentioned receptacle. 115
45. 13. In dental apparatus, a hollow pedestal having an extension provided with an opening, a liquid outlet conduit within the pedestal having its receiving end connected with the extension within the opening, a hollow arm connected at one end with said conduit end, a basin on the arm in communication therewith, means for delivering liquid to the basin, a receptacle on the extension surrounding the receiving end of the outlet conduit, and a second receptacle extending beneath the arm and arranged to receive the condensate accumulating upon and discharging from the arm and to deliver the same to the first mentioned receptacle. 120
50. 14. In dental apparatus, a hollow pedestal having an opening in its wall provided with a surrounding seat, a receptacle positioned upon the seat, a ring disposed upon the wall of the receptacle, a tubular mounting element disposed within the opening of the pedestal and having a part serving to hold the ring on the receptacle, adjustable means connected with the mounting element for securing it upon the pedestal, a hollow arm having one end connected with the ring and communicating with said mounting element, a liquid discharge conduit connected with the mounting element, and means for delivering liquid to the arm, said receptacle being arranged to receive a portion of the condensate accumulating upon and discharging from the exterior surface of the arm. 125
55. 15. In dental apparatus, a hollow pedestal having an opening in its wall provided with a surrounding seat, a receptacle positioned upon the seat, a ring mounted upon the receptacle, a

- 5 tubular mounting element disposed within the opening of the pedestal and having a part serving to hold the ring on the receptacle, adjustable means connected with the mounting element for securing it upon the ring, a hollow arm having one end connected with the ring and communicating with said mounting element, a liquid discharge conduit connected with the mounting element, means for delivering liquid to the arm, 80
- 10 said receptacle being arranged to receive a portion of the condensate accumulating upon and discharging from the exterior surface of the arm, a second receptacle overlying the body of the pedestal and extending beneath the arm arranged to receive a portion of the condensate accumulating upon and discharging from the arm, the first mentioned receptacle being arranged to discharge the liquid received therein to the second mentioned receptacle, and means for conveying the liquid from the second mentioned receptacle to the discharge conduit. 85
- 15 16. In dental apparatus, a pedestal, a hollow arm connected with the body of the pedestal, a cuspidor bowl on the arm communicating therewith, an outlet conduit connected with the arm, valve means connected with the arm, a water supply conduit leading through the pedestal to and from the valve means for control by the latter and arranged to discharge into the cuspidor bowl, and a receptacle underlying the arm arranged to receive the condensate accumulating upon and discharging from the arm. 90
- 20 17. In dental apparatus, a pedestal, a hollow arm connected with the body of the pedestal, a cuspidor bowl on the arm communicating therewith, an outlet conduit connected with the arm, a receptacle extending above a portion of the body of the pedestal and underlying the arm arranged to receive the condensate accumulating upon and discharging from the arm, valve means on the arm, a water supply conduit leading through the pedestal and the receptacle to and from the valve means for control by the latter arranged to discharge into the cuspidor bowl, and a drain pipe extending from the receptacle and connected with said outlet conduit. 95
- 25 18. In dental apparatus, a pedestal provided with an opening in its wall having a surrounding seat, a drip-catching receptacle on the seat, a hollow arm having its outlet end in registry with the opening, a tubular mounting element within the opening communicating with said outlet end of the arm and connected therewith, a discharge conduit leading from the mounting element, a liquid holding receptacle on the arm, and means arranged to deliver liquid to the last mentioned receptacle. 100
- 30 19. In dental apparatus, a pedestal having an opening in its wall, a hollow arm extending above and having its lower end overlying the opening, a drain pipe within the pedestal communicating with the lower end of said arm through said opening, a discharge conduit leading from the mounting element, a receptacle beneath the arm arranged to receive the condensate accumulating on and discharging therefrom, a second receptacle on the arm communicating therewith, and liquid supply means arranged to discharge into said last mentioned receptacle. 105
- 35 20. In dental apparatus, a pedestal having an opening in its wall, a hollow arm having its outlet end overlying the opening, a receptacle on the arm communicating therewith, a tubular mounting element within the opening communicating with the outlet end of said arm and rotatably receiving the arm, a discharge pipe leading from said mounting element, a water supply pipe extending upwardly through the pedestal and having a terminal portion within the mounting element on the pivotal axis of the arm, valve means within the arm, a conduit beneath the arm having its inner end extending through the wall of the arm and rotatably received by the terminal portion of the supply pipe and having its upper end connected with said valve means, a drip catching receptacle beneath the arm and conduit adapted to receive the condensate accumulating upon and discharging from said arm and conduit and a conduit extending from and controlled by the valve means arranged to discharge within the first mentioned receptacle. 110
- 40 21. In dental apparatus, a pedestal provided with a hollow extension, a hollow arm having an outlet end overlying the extension, a tubular mounting element within the extension communicating with and connected to the outlet end of the arm, a conduit leading from the tubular mounting element, a liquid holding receptacle mounted on and communicating with the arm, liquid supply means adapted to discharge the liquid into the receptacle comprising a conduit projecting upwardly through the pedestal and through the mounting element into the arm and having an angular connection extending through the wall of the arm, and a drip catching receptacle underlying said arm and said connection adapted to receive the condensate accumulating upon and discharging from said arm and connection. 115
- 45 22. In dental apparatus, a pedestal having an opening in its wall, a hollow arm having one end overlying said opening, a tubular mounting element within the pedestal communicating with and rotatably receiving said arm end and serving to connect it with the pedestal, a discharge conduit leading from the mounting element, a receptacle on the arm communicating therewith, liquid supply means arranged to discharge into the receptacle comprising a conduit extending into said end of the arm in coaxial relation therewith and having an extension projecting through the wall of the arm and adapted to swing with the latter about the axis thereof, and a drip catching receptacle underlying said arm and the extension of said conduit and adapted to receive the condensate accumulating upon and discharging from the arm and the extension. 120
- 50 23. In dental apparatus, a pedestal having an opening in its wall, a hollow arm having its outlet end overlying the opening, a tubular mounting element within the opening communicating with the outlet end of said arm and rotatably receiving the arm, a discharge conduit leading from the tubular mounting element, a receptacle on the arm communicating therewith, water supply means arranged to discharge into the receptacle comprising a fixed pipe extending into the mounting element on the axis of the arm and having a rotary extension projecting exteriorly of the arm and discharging into the receptacle, and a drip catching receptacle underlying said arm and said rotary extension adapted to receive the condensate accumulating upon and discharging from the arm and the rotary extension. 125
- 55 24. In dental apparatus, a pedestal, a tubular arm for receiving and discharging liquid, said arm being connected with the pedestal and extending above a portion thereof and having an outlet for the liquid in its lower end, and drip catching means underlying the arm adapted to 130
- 60 25. In dental apparatus, a pedestal having an opening in its wall, a hollow arm having its outlet end overlying the opening, a receptacle on the arm communicating therewith, a tubular mounting element within the opening communicating with the outlet end of said arm and rotatably receiving the arm, a discharge conduit leading from the tubular mounting element, a water supply pipe extending upwardly through the pedestal and having a terminal portion within the mounting element on the pivotal axis of the arm, valve means within the arm, a conduit beneath the arm having its inner end extending through the wall of the arm and rotatably received by the terminal portion of the supply pipe and having its upper end connected with said valve means, a drip catching receptacle beneath the arm and conduit adapted to receive the condensate accumulating upon and discharging from said arm and conduit and a conduit extending from and controlled by the valve means arranged to discharge within the first mentioned receptacle. 135
- 65 26. In dental apparatus, a pedestal having an opening in its wall, a hollow arm having its outlet end overlying the opening, a receptacle on the arm communicating therewith, a tubular mounting element within the opening communicating with the outlet end of said arm and rotatably receiving the arm, a discharge conduit leading from the tubular mounting element, a water supply pipe extending upwardly through the pedestal and having a terminal portion within the mounting element on the pivotal axis of the arm, valve means within the arm, a conduit beneath the arm having its inner end extending through the wall of the arm and rotatably received by the terminal portion of the supply pipe and having its upper end connected with said valve means, a drip catching receptacle beneath the arm and conduit adapted to receive the condensate accumulating upon and discharging from said arm and conduit and a conduit extending from and controlled by the valve means arranged to discharge within the first mentioned receptacle. 140
- 70 27. In dental apparatus, a pedestal having an opening in its wall, a hollow arm having its outlet end overlying the opening, a receptacle on the arm communicating therewith, a tubular mounting element within the opening communicating with the outlet end of said arm and rotatably receiving the arm, a discharge conduit leading from the tubular mounting element, a water supply pipe extending upwardly through the pedestal and having a terminal portion within the mounting element on the pivotal axis of the arm, valve means within the arm, a conduit beneath the arm having its inner end extending through the wall of the arm and rotatably received by the terminal portion of the supply pipe and having its upper end connected with said valve means, a drip catching receptacle beneath the arm and conduit adapted to receive the condensate accumulating upon and discharging from said arm and conduit and a conduit extending from and controlled by the valve means arranged to discharge within the first mentioned receptacle. 145
- 75 28. In dental apparatus, a pedestal, a tubular arm for receiving and discharging liquid, said arm being connected with the pedestal and extending above a portion thereof and having an outlet for the liquid in its lower end, and drip catching means underlying the arm adapted to 150

receive the condensate accumulating upon and discharging from the arm.

25. In dental apparatus, a pedestal, a tubular arm for receiving and discharging liquid, said arm being connected with the pedestal and extending above a portion thereof and having an outlet for the liquid at its point of connection with the pedestal, a drain connection leading from the outlet end of the arm, and drip catching means underlying the arm including a part interposed between the pedestal and the arm at their point of connection, said drip catching means being adapted to receive the condensate

accumulating upon and discharging from the arm.

26. In dental apparatus, a pedestal, a tubular arm for receiving and discharging liquid, said arm being connected with the pedestal and extending above a portion thereof, a drain pipe connected with the arm, drip catching means overlying said portion of the pedestal including a receptacle inserted between the arm and pedestal at their point of connection, and a drain tube leading from the drip catching means and discharging within the drain pipe. 80 85
